GARMENT PRESS

Arthur D. Benson, Los Angeles, Calif.

Application February 19, 1946, Serial No. 648,633

2 Claims. (Cl. 38—71)

1

This invention has to do with a garment press and it is a general object of the invention to provide a press particularly useful for pressing garments such as trousers.

It is desirable to maintain certain garments or items of wearing apparel in a neatly pressed condition this being particularly true of men's trousers and women's slacks. It is common to press such garments occasionally with an iron and then hang them when not in use so that they hang straight and maintain, as far as possible, the pressed condition.

It is a general object of this invention to provide a garment press in which garments can be stored or placed overnight so that a press initially established can be effectively maintained. With the press that I have provided the garment does not merely hang in a suitable position but the creases established by pressing are tightly held so that when the garment is removed for use the original press has been maintained.

A general object of the invention is to provide a device of the general character referred to which can be hung in a closet or the like in much the manner that trousers are ordinarily hung when not in use, or which can be stored in any desired position. With the device that I have provided it is not necessary that it be hung up when the garment is in it, but it is equally effective when placed in any convenient position.

A further object of the present invention is to provide a garment press of the general character referred to that involves few simple inexpensive parts. The device of the present invention involves, essentially, a baseboard, a press board, and a spring clamp means by which the press board is held over a garment arranged on the baseboard so the garment is effectively clamped or pressed.

It is a further object of my present invention to provide a garment press of the general character referred to that is very simple and convenient to operate. Through the construction that I have provided the simple parts that are involved are easily and quickly arranged together in a manner to effectively clamp a garment, and can be very easily and quickly disengaged to remove the garment when it is desired for use.

The various objects and features of my invention will be fully understood from the following detailed description of typical preferred forms and applications of my invention, throughout which description reference is made to the accompanying drawings, in which:

Fig. 1 is a front or face view of the garment

press that I have provided, showing a pair of trousers arranged therein. Fig. 2 is an edge or side elevation of the device, as shown in Fig. 1. Fig. 3 is a reduced front view of the base board 10 of the press showing the other parts of the structure removed therefrom. Fig. 4 is a face or front view of the press board showing it apart from the other elements of the structure. Fig. 5 is a face or front view of the spring clamp unit employed to clamp the press board to the garment arranged on the baseboard, showing the spring unit removed from the other elements of the structure and in the position that it assumes when removed from the other parts of the structure. Fig. 6 is an edge view of the spring unit, being a view taken as indicated by line 6—6 on Fig. 5. Fig. 7 is an enlarged detailed transverse sectional view of the structure being a view taken as indicated by line 7—7 on Fig. 1. Fig. 8 is an enlarged detailed sectional view taken as indicated by line 8—8 on Fig. 1. Fig. 9 is an enlarged view taken as indicated by line 9—9 on Fig. 1. Fig. 10 is an enlarged detailed sectional view taken as indicated by line 10—10 on Fig. 1, and Figs. 11 and 12 are side views and plan views, respectively, showing a modified latch means that may be employed in carrying out the invention.

The press that I have provided can be used to advantage to hold or press various garments. However, since it is particularly useful for handling trousers I will describe it in a form designed for such garments and will refer to it as a trouser press, but do not wish to thereby restrict or limit its use to any particular type or form of garment.

The press involves, generally, three principal elements, namely a baseboard 10, a press board 11 and a spring unit 12 which acts to yieldingly urge the press board toward the baseboard, so that a garment between the parts is effectively pressed. The construction involves other elements such as hook means 13 by which one end of the spring unit is hooked to the base board and latch means 14 by which the other end of the spring unit is latched to the baseboard.

The base board 10 includes a flat plain board or panel 15 having a flat smooth face 16 to receive the garment G to be pressed. The panel 15 may be a plate or panel of metal or it may be formed of wood. In practice it is advantageous to form the panel 15 of a sheet of plywood which is sufficiently heavy to be rigid under the conditions hereinafter described. The panel 15 may be of any size and shape so long as it is sufficiently large to accommodate the portion of the garment

G which is to be pressed. In the case of a trouser press such as I am describing it is desirable to taper the panel so that it corresponds generally to the shape of the trousers to be pressed when the trousers are laid out flat or in the position in which they are ordinarily hung. The panel 15 is made long enough to amply accommodate the portion of the garment to be pressed, which in the case of a pair of trousers is the leg portion, and it is made wide enough to accommodate the width of the garment, leaving a margin at either side.

The baseboard 10 preferably includes, in addition to the panel 15, side rails 18 which extend lengthwise of the side edges of the panel and serve as a stiffening or reinforcing means for the panel 15. In the particular case illustrated the rails 18 are shown rectangular in cross section and are grooved at 19 to receive the edges of the panel 15. The rails 18 are formed of wood or metal and are so proportioned as to effectively stiffen and reinforce the panel 15 and they are made such as to accommodate the means 13 and 14 as will be hereinafter described.

The base board 10 is preferably provided at one end with a handle extension 20. In the case of a trouser press such as I have illustrated it is desirable to provide the handle extension 20 at the narrow or small end of the board, which end of the structure will be referred to as the upper end, since it is the end that will be up when the device is hung in a closet or the like. The handle extension 20 may be formed by an integral continuation of the panel 15 in which there is an opening or aperture 21 formed to leave a transverse part 22 which forms a convenient grip by which the device can be handled. It is desirable, in practice, to provide a means to facilitate hanging the structure and this means may involve a simple hanger or hook 23 carried by the grip portion 22 to project therefrom, as clearly shown in Figs. 1 and 2 of the drawings. In the preferred form of the invention the hook 23 is looped at 23^a to engage a pin 22^a secured to the grip as shown in Fig. 1. The hook can then be folded back upon the baseboard 10 so that it does not afford an obstruction when not in use.

The press board 11 is in the nature of a cover or pressure plate that is arranged over the garment after it has been applied to the baseboard 10. The press board is preferably shaped and proportioned to correspond, generally, to the shape and proportioning of the panel 15 of the baseboard. Where the panel 15 is tapered to correspond to the shape of the legs of a pair of trousers the press board is correspondingly shaped as I have shown in Fig. 4 of the drawings. In practice it is advantageous to make the press board a simple plain board shaped substantially as shown in Fig. 4 and having a smooth face 24 to oppose the face 16 of the base board.

The spring unit 12 is adapted to be connected to the baseboard 10 by the means 13 and 14 so that it engages the press board 11 to yieldingly urge it toward the face 16 of the baseboard. In the preferred form of the invention the spring unit involves one or more leaf springs 30 and the unit has projections at its ends to cooperate with the means 13 and 14. In the construction illustrated the spring unit involves two leaf springs 30 joined at one end by a cross bar 31 and at the other end by a cross bar 32. Where the press board 11 and the baseboard 10 are tapered, as shown in Figs. 3 and 4, it is desirable to arrange the springs 30 so the spring unit is shaped to

correspond to the boards. In the particular case illustrated the spring units 30 are angularly related so that they are close together at one end where they are joined by the bar 31 and are wide apart at the other end where they are joined by the bar 32.

The bar 31 which joins the ends of the springs 30 at the narrow end of the structure may be joined or coupled to the springs in any suitable manner. In the case illustrated the springs have end portions 33 that are wrapped around or which embrace the rod 31. The rod 31 serves to form the projections for cooperating with the means 14. For this purpose the end portions 34 of the rod 31 project from the springs 30 as clearly shown in Fig. 5 of the drawings. The rod 32 which joins the springs 30 at the wide end of the structure may be joined with the springs in any suitable manner. In the case illustrated the springs have portions 35 that wrap around or embrace the rod to hold it. The rod 32 has end portions 36 projecting from the springs 30 to form projections which cooperate with the means 13.

The springs 30 are leaf springs and are preferably fabricated from thin spring steel bowed or made concavo-convex as shown in Fig. 6. With the spring unit bowed as just described and as clearly shown in Fig. 6, the desired pressure against the press board 11 is gained when the unit is flexed to a flat position where it bears on the press board throughout its length.

The hook means 13 provided for releasably coupling the spring unit to the base board is confined to one end of the structure, preferably to the large or wide end, as shown in the drawings, and it preferably involves a hook at each edge of the structure or, in other words, a hook to hold each of the projections 36. In the preferred construction illustrated the two units of the hook means 13 are located at the rails 18. The structure illustrated in Fig. 10 involves a notch 40 in each rail and a plate 41 attached to the top of the rail as by screws 42, so that it has a tongue 43 overhanging the notch forming a recess between the bottom of the notch and the tongue, in which the projections 36 can be retained. The notches 40 are at the ends of the rails 18 so that the recesses just described open at the end of the structure. To apply the spring unit to the hook means it is merely necessary to engage projections 36 at the wide end of the spring unit under the tongues 43. If desired the outer ends 45 of the tongues can be bent in slightly so that the projections will not become accidentally displaced and making it necessary that the tongues be flexed somewhat in applying the projections to or removing them from the recesses.

The latch means 14 is located at the other end of the structure and in the case illustrated is at the narrow end of the structure. The latch means 14 is preferably formed of two units or brackets to engage the two projections 34 of the spring unit and each latch unit may involve a simple latch plate 50 with a flange 51 secured to the underneath portion of panel 15 of the base board, as by screws 52. Each bracket has a projecting spring tongue portion 53 with an aperture 54 to receive one of the projections 34. It is preferred that the upper or projecting end portion of each tongue 53 be turned outwardly somewhat as shown in Fig. 8 to facilitate latching of the projection 34 into the opening 54. When the parts are arranged as shown in Fig. 8 the spring unit is effectively latched to the

baseboard and it will be apparent that the spring unit can be readily released by merely deflecting the tongues 53 outwardly in the direction indicated by the arrow A in Fig. 8.

The modified form of latch means illustrated in Figs. 11 and 12 involves a loop or ring 60 pivotally carried by the baseboard to be swung between an "in" position where it overhangs the projection 34 and an "out" position such as is indicated in dotted lines in Fig. 12, where it clears the projection 34 allowing the spring unit to be free of the base part.

In using the press that I have provided the trousers or other garments to be pressed can be carefully laid on the surface 16 of the panel 15 so that the creases occur in the manner finally desired. The press board 11 is then arranged over the garment so the garment is confined between the board 11 and the panel 15. To gain the desired pressure or clamping action between the press board 11 and the panel 15 the spring unit 12 is first hooked to the board 10 by the means 13 by engaging the projections 36 under the tongues 43. The other or narrow end of the spring unit is then pressed down or toward the press board 11 until the projections 34 latch into the openings 54 of the tongues 53, or until they are in a position to receive the rings 60 if the modified form of construction is employed. With the latch means engaged to hold the projections 34 the structure is set with the garment effectively clamped between the board 11 and the panel 15 and it can be handled in any suitable manner. For instance it can be arranged in a trunk for transportation, or it can be laid in any desired position, or it can be conveniently hung by means of the hook 23 so that it hangs in a closet or on a hook in much the manner that trousers are ordinarily hung. When it is desired to use the garment or to remove it from the press it is merely necessary to disengage the latch means from the projections 34, then unhook the projections 36 from the tongues 43, whereupon the panel 11 is free to be moved from the garment so the garment can be lifted from the panel 15.

Having described only typical preferred forms and applications of my invention, I do not wish to be limited or restricted to the specific details herein set forth, but wish to reserve to myself any variations or modifications that may appear to those skilled in the art and fall within the scope of the following claims.

Having described my invention, I claim:

1. A press of the character described includ-

55

ing, an elongate base board, an elongate press board overlying the base board to clamp a garment thereto, an elongate spring unit overlying the press board, and means releasably coupling the ends of the spring unit to the base board to yieldingly urge the press board toward the base board, the spring unit including two elongate laterally spaced leaf springs and bars connecting the springs at the ends of the unit and having laterally projecting ends at the ends of the unit, the said means including hooks at the corners of the base board at one end thereof receiving the projecting ends of the bar at one end of the unit and latches at the corners of the base board at the other end thereof receiving the projecting ends of the bar at the other end of the unit, the base board including a flat panel and rails at the longitudinal edges of the panel reinforcing the panel, the said hooks being carried by the rails.

2. A press of the character described including, an elongate base board, an elongate press board overlying the base board to clamp a garment thereto, an elongate spring unit overlying the press board, and means releasably coupling the ends of the spring unit to the base board to yieldingly urge the press board toward the base board, the spring unit including two elongate leaf springs and bars connecting the springs at the ends of the unit and having ends projecting laterally of the unit at the ends of the unit, the said means including hooks receiving said projecting ends at one end of the spring unit and spring latches operating transversely of the press receiving said projecting ends at the other end of the spring unit, the base board including a panel and rails at the longitudinal edges of the panel reinforcing the panel, the said hooks and latches being carried by the rails.
